UNITED STATES PATENT OFFICE

2,478,460

TOBACCO CURER

Masten B. Collins, Claudeville, Va.

Application March 20, 1946, Serial No. 655,840

1 Claim. (Cl. 263—40)

1

This invention relates to a tobacco curer for installation in a conventional tobacco barn.

An important object of the invention is the provision of a device of this character that will thoroughly distribute the heat over the interior of the barn.

Another object of the invention is the provision of a device of this character that is simple in construction, durable in use, efficient in operation and can be manufactured inexpensively.

With the above and other objects and advantages in view the invention consists of the novel details of construction, arrangement and combination of parts more fully hereinafter described, claimed and illustrated in the accompanying drawings in which:

Figure 1 is a plan view of an embodiment of the invention installed in a tobacco barn;

Figure 2 is a sectional view on the line 2—2 of Figure 1;

Figure 3 is a sectional view on the line 3—3 of Figure 1;

Figure 4 is a sectional view on the line 4—4 of Figure 1;

Figure 5 is an enlarged fragmentary view of the bent portion of the flue;

Figure 6 is a sectional view of one of the heat vents and

Figure 7 is a sectional view on the line 7—7 of Figure 6.

Referring more in detail to the drawings the reference numeral 10 designates the tobacco barn in which the tobacco curer 12 forming an embodiment of the invention as installed and which comprises the fire box 14 which is fired from the open rear end 16. The front wall 18 of the fire box is provided with the pipe coupling 20 and the top 22 and side walls 24 of the fire box 14 engage the wall 26 of the barn being built therein. A flue 28 is connected to the coupling 20 and extends longitudinally of the barn for practically the entire length thereof and then is bent at 30 to extend in parallel relation with the end wall 32 and then bent at 34 is extended in parallel relation with the first portion to be connected at its free end to the pipe coupling 36 in the chimney 38 which is constructed exteriorly of the barn but engages the wall 26. Positioned immediately below the coupling 36 in the chimney 38 is a second pipe coupling 40 which is connected to a flue 42 which extends longitudinally of the barn the same distance as flue 28 and is in inclined relation therewith. The flue 42 at its free end is provided with a removable cap closure 44 and at predetermined spaced relation to each other cutouts 46 are provided in the flue to support the screens 48. The upper marginal edge of the cutouts 46 are provided with channel flanges 50 in slidably receive the dampers or doors 52 and

2

the chimney 38 is provided with a pivoted damper 54 at the top thereof.

In operation fuel 56 preferably wood is placed in the fire box 14 and ignited. Heat from the fire box 14 will travel through the flue 28 in the direction of the arrows to the chimney 38 from where it will be dissipated into the atmosphere. However, if more intense heat is required in the barn the damper 54 is closed and the heat will travel through the flue 42 and emerge through the cutouts 46 and screens 48 into the interior of the barn.

It has been the usual custom to just build a fire and permit the heat to circulate without means for distributing the heat through the barn thus the present invention which provides the flues that extends and nearly covers the length and breadth of the barn and rest on the earth floor 58 of the barn is believed to be an improvement over the prior methods employed.

It is believed that the construction and operation of the invention will be apparent to those skilled in the art and it is to be understood that changes in the details of construction, arrangement and combination of parts may be resorted to provided they fall within the spirit of the invention and the scope of the appended claim.

Having thus described the invention, what is claimed as new and desired to be secured by Letters Patent is:

A device of the character described, in combination with a tobacco barn of a fire box, a U-shaped flue extending for the length and partial breadth of the barn connected to said fire box at one end thereof, a chimney for said barn, the other end of said flue being connected to said chimney, a second longitudinal flue connected to said chimney below said first flue, screened openings in said second flue for distributing heat from said flue into the interior of the barn, sliding dampers cooperating with said openings to control the heat entering the barn, a damper in said chimney for controlling the heat within the barn and means for connecting said flue to said fire box and said first and second flues to said chimney.

MASTEN B. COLLINS.
